UNITED STATES PATENT OFFICE.

WAYNE A. BECKER, OF CINCINNATI, OHIO.

SWIMMING-POOL SCUM-GUTTER-OVERFLOW CONTROL.

Application filed August 30, 1926. Serial No. 132,411.

The invention relates to means particularly adapted to control the flow of water from sources.

The objects of the invention are to provide a simple, efficient, economical, and durable means adapted to automatically permit a predetermined quantity of water, over a given period, to be conveyed, simultaneously from a plurality of sources; and to provide means whereby the relative rate of flow, capacity or quantity of water which flows each period from one source of said pool is automatically controlled by the relative rate of flow, capacity or quantity of water which flows each period, from another source of said pool.

Other objects will be apparent as the description proceeds.

The invention consists in the combination arrangement of the parts and in the details of the construction, as hereinafter set forth and claimed.

In the drawings:

Fig. 1 is a plan view of a swimming-pool basin, with parts broken away;

Fig. 2 is a section taken on a line corresponding to 2—2 in Fig. 1;

Fig. 3 is a section taken on a line corresponding to 3—3 in Fig. 1;

Fig. 4 is a plan view of the scum gutter overflow control;

Fig. 5 is an end elevational view of the same;

Fig. 6 is a section taken on a line corresponding to 6—6 in Fig. 4;

Fig. 7 is the same view shown in Fig. 6 but with the valve mechanism in changed position and with parts broken away; and

Fig. 8 is a section taken on a line corresponding to Fig. 8 in Fig. 6 and with parts broken away.

The preferred construction of the invention is exemplified with usual swimming-pool basin 1 comprising side walls 2 and 3, end walls 4 and 5, and bottom 6 which may be constructed of concrete, or other suitable water retaining material. The walk 7 which is shown surrounding the basin may be constructed of concrete, or other suitable material, and may be included or not in the structure, as desirable.

The usual scum gutter 8 extends completely around basin 1 and is formed in the end walls and the side walls at a sufficient distance above bottom 6 to conform with the required depth of the water 9 usually con-

tained in the basin, whereby when the level or surface 10 of water 9 is slightly higher than the outer side 11 of the scum gutter, the top surface of the water is adapted to drain into the gutter, thereby carrying the foreign matter such as oil, dirt, grass, rubbish, and the like, from the surface of the pool.

Adjacent end wall 5, of the basin, is compartment 12 comprising bottom 13, side walls 14 and 15, end walls 5 and 16, and top 17 which is flush with the top 18 of the basin.

Within compartment 12 are filtering units 19 suitably connected by pipe 20, as usual with pump 21. The filtering units, also, are suitably connected as usual with pipe 22 which leads through wall 5, or if desirable it may be carried through walls 2, 3, 4 and 5 of basin 1, whereby after the water is forced, under pressure, through the filtering units it is again returned into the basin.

The water 9 is adapted to be returned to the filtering units through pipes 24 and 25, respectively, connected with scum gutter 8 and main drain outlet or pipe 26 which leads through bottom 6 of the basin. The pipe 24 is of smaller diameter than pipes 25. The opposite ends 27 and 28, respectively, of pipes 24 and 25, are connected with gate valves 29 and 30, respectively, communicating with inlets 31 and 32, respectively, of chambers 33 and 34 of casing 35 of scum gutter overflow control 36.

Secured to top 37 of casing 35 and communicating with opening 38, in the casing, is reducer 39 having its upper end 40 secured, by bolts 41, to lower end 42 of reservoir 43 having cap 44 suitably secured to its upper end 45. Projecting through hole 46, in the cap, is tube 47 having its upper end 48 protruding through hole 17 in top 17 and flush with the top of the compartment 12.

Inside reservoir 43 is a copper, or other suitable material hollow body or float 49 capable of movement longitudinally inside the reservoir. Fixed to the bottom 50 of the float is valve stem 51 which is maintained in position centrally of the reservoir, as by being slidably received in hole 52 in guide 53 secured in position between ends 40 and 42, respectively, of reducer 39 and reservoir 43. The guide 53 is webbed formed to permit the free passage of water through holes 53' from reducer 39 into reservoir 43, and vice versa.

The valve stem may be formed in sections

and secured together by means of union 55, if desirable, to facilitate in assembling the control 36.

Suitably secured to bottom 56 of valve 5 stem 51 is compound valve head 57 consisting of spaced apart heads 58 and 59, suitably fixed to the valve stem. The heads 58 and 59, respectively, comprise plates 60 and 61, respectively, having ribs 62 and 63 integrally connected therewith, and slidably mounted in holes 64 and 65, respectively, in top and bottom walls 66 and 67 integrally connected with rear wall 68. The walls 66, 67 and 68 have their sides integrally formed 10 with sides 66' of casing 35. The front edges of walls 66 and 67 are integrally connected with front 69 of the casing, whereby compartment 70 is formed with inlet 32, of chamber 34, communicating with the compartment:

The heads 58 and 59, respectively, are positioned as shown in Fig. 6, with the outer edges of plates 60 and 61 in close engagement with seats 71 and 72 of walls 66 and 25 67 only when the pump is not operating. When the valve is partly open, but not fully, a relative small quantity of water is adapted to flow from main drain outlet 26.

However, when the heads 58 and 59 are 30 positioned as shown in Fig. 7, with plates 60 and 61 disengaged from seats 71 and 72, the water of the full capacity of pump 21 is adapted to flow from basin 1, through drain pipe 26, pipe 25, valve 30, compartment 35 70, chamber 34 and thence into pump 31, through pipe 73 which connects the pump with outlet 74 of chamber 34 of casing 35. The plate 75, suitably secured, to casing 35, prevents the water from escaping 40 from chamber 33 through hole 33' in the casing.

When the level of the surface of water 9, in basin 1, is sufficiently high to permit its flow over side 11 and into scum gutter 8, 45 the water is adapted to flow from the scum gutter through pipe 24, valve 29, casing 35 and pipe 73 into pump 21, whereby the surface of the water which flows into the scum gutter is conserved by being filtered and returned into basin 1, as previously explained. Inasmuch as the water flows from basin 1 50 into scum gutter 8 with practically no water-head, an insufficient quantity of water would flow from the scum gutter into pump 21, if pipe 24 were connected directly with pipe 25. Therefore, the control 36 is utilized to 55 restrict or retard the flow of the water from main drain outlet 26 to permit the water to flow from the scum gutter into 60 the pump through pipe 73 which also communicates with pipe 25 and outlet 26.

The control 36 is positioned below the level of water 9, so that float 49 approximately is on a level determined by subtracting 65 from the level of the water 9, the dis-

tance equal to the respective waterhead caused by the restriction or resistance of the pipes and inlets to the flow of the water from the scum gutter to casing 35, and also in consideration of the respective quantities 70 of water, over a given period, desired to be received into pump 21 from each of the scum gutter and main drain outlet sources, whereby float 49 being adapted to operate valve head 57, the quantity flow of the water from the main drain outlet is automatically restricted or retarded proportional to the level of the surface of the water in basin 1, with relation to outer side 11 of the scum gutter.

When the float, which is in reservoir 43, is positioned to partly stop the flow of the water from pipe 25, the result is caused by the level of the surface of the water in the basin being sufficiently high that a quantity of water is flowing from the scum gutter, whereby the water communicated to the reservoir causes the float to rise in reservoir 43, thereby operating valve head 57 so that only the required quantity of water will flow 90 from the main drain outlet.

For example, if the level of the surface of the water in basin 1 is near or below side 11 of the scum gutter whereby less than the required quantity of water, or none flows, 95 into the scum gutter, or if the valve 29 is manually closed, the level of the water in the reservoir is lowered, thereby lowering float 49 which causes plates 60 and 61 to disengage from seats 71 and 72 and permits pump 21 to draw its capacity of water from the main drain outlet, until the level of the water in the basin rises which causes the float to rise, thereby operating valve head 57 with relation to the valve seats 71 105 and 72 and retards the flow of the water from outlet 26.

If, for illustration, it is desired that 50% of the water received by the pump 21 shall normally flow from the scum gutter, and 50% from the main drain outlet, then the scum gutter piping system is designed so that when 50% of the flow of water to the pump is from the scum gutter source, the restrictions or resistance to the flow from the outlet is equivalent to the difference in the waterheads of the two sources. In other words, the water from the scum-gutter flows unobstructedly through the control, but the quantity of water over a given period which flows through the control from drain 26 is controlled and dependent upon the quantity of water, over a given period, which flows through the control from the scum-gutter source. And if no water is being received by the control from the scum-gutter, then the full capacity of the pump is received through the drain 26. But a predetermined quantity of water, proportional to the quantity being received from drain 26, is per-

mitted to flow through the control from the scum gutter. The limit of the proportional flow of water from the scum-gutter to the pump is controlled by the water head 5 and the size of pipe 24.

The important feature of the invention is that water being received from two sources is discharged from a common outlet, and the proportion of the water flowing from 10 the outlet from one of the inlets is controlled by the flow or capacity of the water received by the other inlet. If desirable, compensating mechanism and accessories having two inlets may be substituted for 15 the casing 25 and the mechanism described.

The pipes 76 and 77, having usual gate valves 78 and 79 connected therewith, respectively are connected with the water source of supply and the sewer to provide 20 for draining the basin of the pool and filling it with a fresh supply.

It is understood that pipe 24 may have connection with suitable outlets in the walls of a swimming-pool basin, as the important 25 purpose of the pipe 24 is to drain the surface water into the pump, irrespective whether or not the scum gutter 8 or other outlets are utilized for the purpose.

The control 36 may be made of any size, 30 and constructed of any materials deemed convenient and suitable for a device of this character, and while I have illustrated and described a form of construction, and arrangement of parts found desirable in materializing the invention, I wish to include 35 in this application all mechanical equivalents and substitutions and the variety of uses that may fairly be considered to come within the scope of the purview of the invention, as defined in the claims.

What I claim as new and desire to secure by Letters Patent is:

1. A swimming-pool discharge control valve having a pair of inlets and an outlet, 45 the combination of a pair of discharge pipes connected with said valve, and means in said valve adapted to control the capacity of water discharged through said outlet from one of said inlets dependent upon the capacity of water received through the other said inlets.

2. The combination with a pool, of a control valve comprising a casing having a pair of chambers having a pair of inlets 55 communicating with the top and bottom of said pool, said chambers communicating with each other and one of said chambers having an outlet, a valve seat in one of said chambers, a reservoir communicating with said 60 chambers, a float in said reservoir, and a

valve in said casing and operatively connected with said float whereby the flow of water from said pool through one of said inlets is controlled by the flow of water through the other of said inlets. 65

3. In a pool discharge device, the combination with a pair of discharge pipes communicating with the top and bottom of the pool, of a casing having a pair of chambers having inlets and one of said chambers 70 having a compartment therein, a valve seat in the wall of said compartment, the inlets of said chambers communicating with said pipes, respectively, the outlet of one of said chambers communicating with the other of 75 said chambers, and the other of said chambers having an outlet, a reservoir communicating with said chambers and adapted to receive water from said pool and positioned below the level of the surface of the water 80 in said pool, a float in said reservoir, and a valve in said casing and operatively connected with said float and said valve adapted to be automatically operated relative to said seat to control the rate of flow of water from 85 one of said inlets dependent upon the flow of water from the other of said inlets.

4. A control valve comprising a casing having an upper and lower chamber and each of said chambers having an inlet, and an 90 outlet, a compartment in said lower chamber communicating with said upper chamber, a valve seat in the walls of said compartment, a reservoir communicating with said chambers, a float in said reservoir, and a 95 valve head in said casing and connected with said float to operate said head with respect to said seat, whereby the flow of water through one of said inlets is controlled by the flow of water through the other of said 100 inlets.

5. A swimming-pool control valve in combination with a swimming-pool, said valve having a pair of inlets communicating with the top and bottom of said pool and having 105 an outlet, and means in said valve whereby the capacity of water received from said pool through one of said inlets is dependent upon the level of the water in said pool.

6. The combination with a swimming-pool, 110 of a water control device having a pair of inlets communicating with the top and bottom of said pool and having an outlet, and means in said device whereby the capacity of water received from said pool through 115 one of said inlets is dependent upon the capacity of water received through the other of said inlets.

WAYNE A. BECKER.
